COIN CONTROLLED APPARATUS

Heinrich F. Pinkenburg, Newtown Square, Pa.,
assignor to Joseph G. Denny, Jr.

Application December 17, 1932, Serial No. 647,803

7 Claims. (Cl. 194—61)

My invention is designed to provide an improved coin-controlled apparatus that may be advantageously adapted for use in cooperation with any kind of vending machine.

5 It is a primary object of my invention to provide an improved apparatus of this character which is of a simple and durable structure, inexpensive to manufacture and so constructed and arranged as to assure always positive and effective operation under the control of a coin or coins of predetermined value.

Another object of my invention is to provide an improved coin receiving mechanism especially adapted for use in connection with the feeding or dispensing mechanism of a vending machine, and which will so control the latter as to prevent operation without using the proper coin or coins.

Another object of this invention is to provide a coin controlled apparatus of the type stated, 20 having means whereby various coin arrangements may be effected so that newspapers, periodicals and various kinds of articles of different values may be dispensed, as for example, Sunday and daily newspapers.

25 Another object of this invention is to so construct this coin-controlled mechanism that, if more than one coin is to be inserted, the device will not operate until the proper number of coins are put in place.

30 A further object of the invention is to provide an apparatus of the type stated, having means for assuring perfect registering alignment of the coin or coins receiving slots and slotways, and other means for permitting the insertion 35 thereinto of coins of a predetermined value only.

A still further object of my invention is to so construct this apparatus that it will be very compact in its construction and very easy, simple and quick to adjust to receive coins of different values.

40 It is with such objects and purposes as these that my invention is concerned, although, as will appear from the specification, drawings and claims, numerous other advantages are also in contemplation.

45 In the drawings—

Figure 1 is a side elevation of the invention, the casing not being shown;

Figure 2 is a front view of the invention;

50 Figure 3 is a perspective view of a portion of the mechanism comprised in my invention, and

Figure 4 also is a perspective view of a portion of the mechanism comprised in my invention.

Similar numerals refer to similar parts throughout the several views.

55 The apparatus described here may be mounted on the inside of a vending machine or may be enclosed in a separate casing and attached to the outside of any vending machine.

60 However in the drawings, the housing of the vending machine 1, the shaft 2, and the sprocket

3, comprising a member of the mechanism of a vending machine, constitute the frame of the apparatus.

Onto the sprocket 3, which constitutes a member of the vending machine mechanism, is mounted the stop lug 4, held in place by screws 5. Secured to the front side of said stop lug 4, are two angle pieces 6, which are held in place by screws 7 and dowels 8 and form the slotway 9. A spacer 10 is provided to permit the assembly of 10 the two angle pieces 6 and the spacer 10 before putting them into the final position.

To control the movement of the stop lug 4, there is provided a pawl 11, which is pivotally mounted at 12 upon the fixed pivot pin 13. An extension 15 14 is secured to and projects laterally from the pawl 11, and is to serve in a manner soon to be described.

An adjustable lever 15 is pivoted at 16 upon the shaft 2, and is held against sideward motion 26 by the plate 17, which is secured to the housing 1 by the screws 18. Secured to the adjustable lever 15 are the coin seats 19 and 20, and coin slots 21 and 22 of different sizes are cut through the lever 15. 25

In the operation of my invention, one, for example, desiring to purchase a daily newspaper sold for two cents and being vended from the machine of which the wall 1 forms a part, would insert the proper coins 23 and 24 into the slot 25 30 in the wall 1 from whence they would pass through the slot 21 and be guided down by the guide 26 into the slotway 9. There the coin 23 will rest on the seat 20 at 27, and the coin 24 will rest on top of coin 23. The purchaser grasping the handle 35 28 would apply a foreward movement to the coins 23 and 24, which now form a unit with the angle pieces 6, the stop lug 4, the sprocket 3, the shaft 2 and the handle 28. The coin 24 extending from the slotway 9 would engage the extension 14 secured to the pawl 11. The pawl 11 would be thereby lifted and release the stop lug 4 at 29. The movement of the vending machine member can now be continued and, after completing the necessary movement, either full turn or back and 45 fore motion, the stop lug 4 will be resting against the pawl 11 at 30; said portion 30 of the pawl 11, serving at the same time as a stop to limit backward motion of the handle 28 and as a means to provide perfect registering alignment between 50 slots and slot ways. The customer can also buy a daily newspaper for five cents while the apparatus is adjusted for two cents. The five cent piece 31 will rest on the seat 19 at 32, after being inserted through the slot 21 into the slotway 55 9 and will extend thereout to the same height as the one cent piece 24, as can be seen in Fig. 2. The purchaser can now proceed in the manner described before.

It will be seen that upon the movement of the 60

slotway 9, the coins will always be taken off their seat and will drop out through the bottom into a receptacle to be provided below.

The apparatus may be provided with seats and slots for many different coins and can be quickly adjusted. For example, I will now describe the changing of the mechanism from a two or five cent daily newspaper adjustment to a ten cent Sunday newspaper adjustment.

10 The caretaker turns the adjustable lever 15 about its pivot at 16 until the slot 22, which is of a size to take ten cent pieces only, is aligned with the slotway 9 and the coin seat 20, being secured to the adjustable lever 15, will also be 15 moved into position to serve as a seat for a ten cent piece. To assure a perfect registering alignment between the slots in the adjustable lever 15 and the slotway 9, a series of holes 33 are placed in the wall 1, which will cooperate with the pin 20 34, of the adjustable lever 15, thus forcing into and holding in predetermined positions the lever 15.

25 The customer will now insert a ten cent piece 35 through the slot 25 in the wall 1, and the slot 22 in the adjustable lever 15, into the slotway 9. Said coin will rest there on the seat 20 at 36, as shown in Fig. 2. The upper edge 30 of the ten cent piece 35 is of sufficient height to engage the extension 14 on pawl 11 as soon as 30 the customer moves the handle 28, and the function of the apparatus will proceed in the manner described before.

35 The adjustable lever 15 may be equipped with many different slots and corresponding seats 35 so as to permit the use of all kinds of different coins of different values.

40 The adjustable member of the apparatus, in this description referred to as a lever, may have the form of a disk, or slider, or the like, therewith 40 providing more space for different coin slots and coin seats.

45 The guide 26 and the side 27 thereof serve as a means for preventing persons from lifting the pawl 11, and therewith unlocking the apparatus by means of a needle etc. from the outside, as it covers access to the pawl 11.

50 The back portion of the pawl 11 is fixed so that it will not permit said pawl to either be lifted too high or dropped too low. The edge 37 prevents it from being lifted too high and the edge 38 prevents it from being dropped too low.

55 It is to be understood that the form of my invention, herewith shown and described, is to be taken as a preferred example of the same and that various changes relative to the material, size, shape and arrangement of parts may be resorted to without departing from the spirit of the invention or the scope of the subjoined claims.

60 Having described my invention, I claim:

1. In a coin-controlled mechanism, the combination with a movable shaft and a detent controlling the movement of said shaft of a member having thereon coin guides for the engagement of faces of coins and a member containing a plurality of coin slots of different sizes and having thereon a plurality of coin stops adapted for the engagement of the edges of coins at different positions in their path of movement between said coin guides, said detent being operable by coins

65 inserted through said slots and positioned by said stops.

70 2. In a coin-controlled mechanism, the combi-

nation with a movable shaft and a detent controlling the movement of said shaft of a member having thereon spaced devices for engaging the faces of coins and a member containing a plurality of coin slots of different sizes and having thereon a plurality of coin stops for the engagement of the edges of coins at different positions along their paths of movement along said devices, said second named member being adjustable relatively to the other member to selectively position one of said coin slots in registration with the space between said devices and to selectively position a complementary coin stop in the path of coins passing along said devices.

75 3. In a coin-controlled mechanism, the combination with a rotatable shaft, a detent therefor and a member forming a coin guide, of a member containing a plurality of coin slots of different sizes and having thereon a plurality of coin stops complementary to the respective coin slots, said second named member being adjustable to selectively position one of said slots in registration with said guide and to position a complementary one of said stops in the path of a coin passing through said guide.

25 4. In a coin-controlled mechanism, the combination with a rotary shaft, a detent controlling said shaft and a member forming a coin passage, of a member containing a plurality of coin slots of different sizes and having thereon a plurality of coin stops respectively obstructing the passage of coins of different sizes at different positions in said passage, said detent being operable by coins positioned by said stop.

35 5. In a coin-controlled mechanism, the combination with a rotatable shaft, a detent controlling said shaft, and a member forming a coin guideway, of a member having thereon a plurality of coin stops and containing a plurality of coin slots of different sizes respectively complementary to said coin stops, said second named member being adjustable relative to the other member to align one of said stops in the path of a coin passing through said guideway and remove the other of said stops out of the path of coins 45 passing through said guideway.

60 6. In a coin-controlled mechanism, the combination of a movable member, a latch controlling the movement of said member, a handle for operating said member, a second member, said handle-operated member having fixed thereon devices forming a coin guide-way and said second member containing a plurality of coin slots of different sizes, one of said members having thereon a plurality of stops adapted to obstruct the 55 passage of coins of different sizes through said guideway, said latch having a part in the path of a coin obstructed in said guideway when moved by said handle.

65 7. In a coin-controlled mechanism, the combination of a shaft, a member on said shaft, a handle on said shaft, a latch normally limiting the movement of said member, devices connected with said member and forming a coin-way, a plate having thereon a plurality of coin stops movable into registration with said coin-way to stop the movement of coins of different sizes through said coin-way at different positions therein, said plate containing a plurality of coin slots of different sizes respectively complementary to the said stops. 70
